W. F. McMONEGAL.
EXTERIOR TIRE ARMOR.
APPLICATION FILED OCT. 11, 1920.

1,373,342.

Patented Mar. 29, 1921.

WITNESS:

ATTORNEY

UNITED STATES PATENT OFFICE.

WILLIAM F. McMONEGAL, OF HAZLETON, PENNSYLVANIA.

EXTERIOR TIRE-ARMOR.

1,373,342.

Specification of Letters Patent. Patented Mar. 29, 1921.

Application filed October 11, 1920. Serial No. 415,981.

To all whom it may concern:

Be it known that I, WILLIAM F. McMONEGAL, a citizen of the United States, residing at Hazleton, in the county of Luzerne and State of Pennsylvania, have invented new and useful Improvements in Exterior Tire-Armor, of which the following is a specification.

The object of my present invention is the provision of a simple, easily applied, efficient and durable exterior armor for tires, and one calculated to increase the tractive capacity of a wheel and prevent skidding thereof in addition to practically precluding the possibility of puncture.

To the attainment of the foregoing the invention consists in the improvement as hereinafter described and definitely claimed.

In the accompanying drawings, hereby made a part hereof:—

Figure 1 is a side elevation showing a portion of a wheel equipped with my improved exterior armor.

Fig. 2 is a view, partly in edge elevation and partly in radial section, of the equipped wheel.

Fig. 2^a is a detail longitudinal section showing the manner of joining the sections or shoes of the armor.

Fig. 3 shows a modified strap designed to be employed in lieu of straps 10.

Fig. 4 is a detail transverse section illustrative of another modification.

Similar numerals of reference designate corresponding parts in Figs. 1, 2 and 2^a.

The wheel illustrated may be and preferably is of the ordinary well known construction, the same being provided with a conventional or any other approved pneumatic tire 1.

My novel exterior armor is formed in a plurality of sections or shoes, and each section includes a body 2 of pressed steel. The said body 2 is curved in the direction of its length and transversely conformably to the tire and is provided at its sides and adjacent to its ends with lateral apertured lugs 3, four in number. At one end the body 2 is provided with a radially disposed flange 4, and the opposite end of the body is slightly offset as indicated by 5 to receive the adjacent end of an adjoining body 2, and is also provided with a radial flange 6, Fig. 2^a.

In addition to the body 2 each armor section 55 comprises calk members 7 on each of which

is a transverse series of calks or teeth 8 separated by intervening spaces 9. This provision manifestly confers on the armor the capacity to prevent skidding of the wheel equipped with the armor. The calk members 7 may be permanently adapted to the body 2 or may be detachably connected to the body, the latter provision being resorted to when deemed expedient so that the calk members may be removed for summer use of the armor or to give place to new calk members when occasion demands. When the sections are assembled in proper working relation on a wheel the plain end of one section body is socketed in the offset end of the body of an adjoining section as clearly appears in Fig. 2^a. It will also be noted that when the sections are assembled as shown in Figs. 1 and 2^a, the flanges 6 by abutting against each other will preclude endwise movement of the sections with respect to each other.

To secure the armor sections on a wheel I provide straps 10 and 11 complementary to each section, the straps 11 being comparatively long and equipped with buckles 12 and the straps 10 being provided at intervals in their lengths with apertures 13. I would also have it here understood that with a view to increasing the durability of the straps it is within the purview of my invention to provide metallic wear plates 14 in the loops of the straps 10 and 11, and to reinforce the apertures 13 in the straps 11 through the medium of metallic eyelets as 90 illustrated.

In applying the armor sections to the wheel I prefer to pass the straps 11 at the inner side of the felly and to the outer side of the wheel, and at the latter point to connect the straps 10 to the buckles 12.

It will be apparent from the foregoing that my novel armor is susceptible of quick and easy application without the assistance of skilled labor or tools, and that when 100 properly applied the armor is adapted in addition to preventing puncture to increase the tractive capacity of the wheel and to effectively prevent any tendency of the same to skid.

In Fig. 3 I show a strap 10^a recessed at 10^b to straddle a spoke of a wheel and having tabs 10^c, designed to coöperate with buckles 12. Said strap 10^a is designed to be used in lieu of the pair of straps 10, Figs. 1 and 2, 110

and is advantageous inasmuch as it is calculated to prevent undue creeping of the anti-skid device about a tire.

It is within the purview of my invention 5 to make each armor section or shoe as shown in Figs. 1 and 2 or as shown in Fig. 4. The armor section 2^x shown in the latter figure is peculiar and advantageous in that it is provided with two longitudinal air chambers 3^x, 10 designed to allow a free circulation of air in order that no undue heat may injure the rubber tire or casing. The said chambers 3^x are afforded by merely bulging the body of the section or shoe 2^x and therefore do 15 not add appreciably to the cost of providing the section or shoe.

Having described my invention, what I claim and desire to secure by Letters-Patent, is:—

An exterior tire armor section or shoe 20 comprising a metallic body curved lengthwise and transversely conformably to a tire and having one of its end portions plain and its other end portion equipped with an offset and also having radial flanges for 25 traction purposes, one of the said flanges being spaced back from the end of the plain portion, and the other flange being disposed at the end of the offset.

In testimony whereof I affix my signature. 30

WILLIAM F. McMONEGAL.
